UNITED STATES PATENT OFFICE.

OLIVER W. TULE, OF HARTFORD, CONNECTICUT.

CUSHION-HEEL FOR BOOTS OR SHOES.

1,091,174.

Specification of Letters Patent. Patented Mar. 24, 1914.

Application filed June 30, 1913. Serial No. 776,611.

To all whom it may concern:

Be it known that I, OLIVER W. TULE, a citizen of the United States, residing at Hartford, in the county of Hartford, State 5 of Connecticut, have invented certain new and useful Improvements in Cushion-Heels for Boots or Shoes; and I do hereby declare the following to be a full, clear, and exact description of the invention, such as will 10 enable others skilled in the art to which it appertains to make and use the same.

The present invention is directed to improvements in cushion heels for boots or shoes, and has for its object to so construct 15 an article of this character that the same can be easily and quickly applied to a heel.

A further object of the invention is to provide a device of this character so constructed that it can be sold at a very small cost, 20 and can be applied by any one not familiar with the art of shoemaking.

With these and other objects in view, this invention resides in the novel features of construction, formation, combination and 25 arrangement of parts to be hereinafter more fully described, claimed and illustrated in the accompanying drawing, in which:—

Figure 1 is a bottom plan view of the device showing it in place upon a heel. Fig. 30 2 is a sectional view on line 2—2 of Fig. 1. Fig. 3 is a similar view on line 3—3 of Fig. 2. Fig. 4 is a similar view on line 4—4 of Fig. 1.

Referring to the drawing, the numeral 1 35 designates the usual leather heel of a boot or shoe, and 2 the cushion heel which is formed from suitable rubber and is molded to correspond to the shape of the heel 1.

A steel plate 3 is embedded in the heel 2, 40 near the upper surface thereof, said plate being provided with openings 4 which receive portions of the material of the heel 2 and assist in holding the plate in place, it being of course understood that the plate is 45 embedded in the heel during the molding process.

The plate 3 is concavo-convex in cross sec-

tion and is provided with a slot 5, through which is adapted to pass the elongated head 6 formed upon the end of the screw 7, said 50 screw being engaged with the heel 1 before application of the heel 2.

Formed in the heel 2 and near the forward edge thereof is a bore 8 which registers with one of the openings 4 formed in said 55 plate, said bore and opening being engaged by a screw 9, which serves to attach the forward end of the heel 2 to the heel 1.

The head 6 of the screw 7 is arranged transversely of the heel 1 and is spaced a 60 slight distance from the lower surface thereof, so that when it is desired to apply the heel 2 the slot 5 formed in the plate 3 is engaged with the head 6 and is then swung so 65 that said slot and head will be arranged at right angles to each other, and as the plate is concavo-convex in cross section the concavity thereof will tend to more firmly bind the plate and head, thus forcing the upper surface of the heel 2 in tight engagement 70 with the lower surface of the heel 1, after which the screw 9 is applied.

What is claimed is:—

In combination with a heel of a boot or shoe having a screw connected thereto, said 75 screw having an elongated head arranged transversely of said heel, a rubber heel having a plate embedded therein, said plate having a slot formed therein and adapted to permit passage of said head therethrough, 80 whereby said rubber heel is swung so that said head is arranged at right angles to the slot, the forward end of the rubber heel having a bore formed therein, and a securing device engageable in said bore and passed 85 through said plate for engaging the first named heel.

In testimony whereof, I affix my signature, in the presence of two witnesses.

OLIVER W. TULE.
